UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

ELECTRIC REGULATOR.

1,320,994.

Specification of Letters Patent.

Patented Nov. 4, 1919.

Application filed April 23, 1917. Serial No. 163,835.

To all whom it may concern:

Be it known that I, WILLIAM A. TURBAYNE, a citizen of the United States, residing at Niagara Falls, in the county of Niagara and State of New York, have invented new and useful Improvements in Electric Regulators, of which the following is a specification.

The present invention relates to electric regulators.

A great deal of difficulty has been encountered in the use of electric regulators where there is encountered a considerable range in the supply voltage and in the load currents, and wherein it is required that there shall be close regulation.

One of the objects of the present invention is to provide a regulator, the resistance of which may be reduced to a minimum when such reduction is desirable, and which will be stable in its operation throughout a wide range of operation.

A further object is to provide a regulator of the compressible pile type which will be satisfactory in operation when the pressure is reduced on the pile, whereby pitting of the blocks will be prevented.

Further objects will be apparent as the description proceeds.

30 The one figure of the drawings represents diagrammatically one embodiment of the present invention.

An electromagnet is represented by the numeral 1. This magnet may be connected across the circuit which it is desired to regulate. The electro-magnet is provided with a pair of pole pieces 2, 3, which should preferably have faces of arcuate outline. Co-operating with the pole pieces 2, 3, is an armature 4, pivoted at the point 5. If desired, the armature 4 may be mounted on ball-bearings whereby friction will be reduced to a minimum. The point of pivotal connection 5 should preferably be midway

45 between the pole pieces 2 and 3. The armature 4 should be provided with pole faces having arcuate outlines to conform with the pole faces of the pole tips 2 and 3. The faces of the magnet pole pieces and the armature should preferably be arcs of circles having the point 5 as a center.

Two carbon piles 6, 6, are provided, which are preferably inclined with relation to each other and to a horizontal line. The carbon piles 6, 6, are provided with relatively fixed

abutments 7, 7. A pressure member 8, of wedge-shaped conformation, is adapted to coöperate simultaneously with both piles to compress them against the fixed abutments 7, 7. It will be apparent that as the pressure member 8 is moved in an upward direction, as viewed in the drawing, such action will compress the carbon piles. When pressure is relieved on the pressure member, the blocks of the carbon pile will tend to separate uniformly throughout the piles, though they will never be entirely out of contact. The pressure member 8 is connected to the armature 4 by means of a thrust member 9. This thrust member 9 has pivotal connection 70 with the pressure member 8 at the point 10 and with the armature 4 at the point 11. The point 10 may be located in a line extending through the pivotal point 5 symmetrical with the remainder of the regulator. The 75 pivot point 11 will be located at a point outside of this line, whereby, as the armature is turned to bring the point 11 more nearly in line with points 5 and 10, the thrust member 9 will exert a toggle action. The armature 4 will be normally held out of line with the pole pieces 2 and 3 by means of the spring 12, whose tension should be adjustable.

As will be apparent from the drawing, the 85 spring 12 will urge the armature 4, and consequently the thrust member 9, into a position to exert pressure upon the compressible piles 6, 6, whereby their resistance is reduced to a minimum. Inasmuch as the 90 thrust member 9 exerts a toggle action, the compressing effect upon the piles 6, 6, may be very considerable. The parts may be so designed that the toggle action of the thrust member 9 will compensate for the increasing 95 mechanical resistance of the piles as their compression increases. A dash-pot 13 may be provided to damp the movement of the armature 4.

It will be clear from the drawing that, in 100 operation, when the electro-magnet 1 is not excited to a high value, the armature 4 will be out of line with pole pieces 2 and 3 and the thrust member 9 will exert a maximum toggle effect to reduce the resistance of the 105 piles 6, 6, to a minimum. As the energization of the electro-magnet increases, the armature 4 will be drawn into alinement with the pole pieces 2, 3, against the tension of the spring 12, thereby withdrawing the 110

wedge-shaped pressure member 8 and allowing the blocks of the compressible piles to separate. By this action, the change of resistance throughout the piles will be uniform, sparking between the blocks will be eliminated, and pitting of the blocks will be prevented. If desired, the regulator, according to the present invention, may be connected in series in the circuit to be regulated through the abutments 7, 7.

It is not desired that the patent should be limited to the exact embodiment of the invention illustrated. Many modifications will occur to those skilled in the art. It is intended in this patent to cover all such modifications that come within the scope of the invention as defined by the appended claims.

What I claim as new and desire to secure by Letters Patent of the United States, is—

1. In combination, a pair of compressible piles inclined to each other and to a horizontal line, a wedge-shaped pressure member adapted to press said piles upwardly to compress same, and a toggle member for operating said pressure member.

2. In combination, a magnet having a pair of oppositely placed pole pieces, an armature pivotally mounted at a point between said pole pieces, a pair of compressible piles inclined to each other, a wedge-shaped compression member coöperating with said piles, a thrust member having pivotal connection

with said compression member and said armature, the point of connection with said armature being different from the point of pivotal mounting of said armature.

3. In combination, a pair of compressible piles inclined to each other, a wedge shaped pressure member coöperating with said piles and a toggle member for operating said pressure member.

4. In combination, an electromagnet having an arcuate pole face, a pivoted armature having an arcuate pole face, said pole faces having approximately the same center, which is the point of pivotal mounting of said armature, a toggle operated by said armature, a wedge operated by said toggle, and a compressible pile operated by said wedge.

5. In combination, an electromagnet having an arcuate pole face, a pivoted armature having an arcuate pole face, said faces having approximately the same center which is the point of pivotal mounting of said armature, a toggle operated by said armature, a wedge operated by said toggle, and a pair of compressible piles inclined to each other and to a horizontal line, said wedge being adapted to simultaneously compress said piles by an upward movement.

In witness whereof, I have hereunto subscribed my name.

WILLIAM A. TURBAYNE.
